UNITED STATES PATENT OFFICE.

FLOYD CALVIN WEAVER, OF WASHINGTON, DISTRICT OF COLUMBIA.

GRINDING MACHINE.

Application filed May 2, 1922. Serial No. 557,938.

To all whom it may concern:

Be it known that I, FLOYD C. WEAVER, a citizen of the United States, residing at Washington, District of Columbia, have invented certain new and useful Improvements in Grinding Machines, of which the following is a specification, reference being had therein to the accompanying drawings.

The object of this invention is to provide a driving mechanism for moving a lapping plate relative to a work carrying plate in a desired orbit and for varying the orbit and the position of the orbit in respect to the work carrying plate so that the grinding may be performed in a desired manner.

With these and other objects in view, my invention comprises certain novel combinations, constructions and arrangements of parts as will be hereinafter described, illustrated in the accompanying drawings, and more particularly pointed out in the appended claims.

In the drawings:

Figure 1 is a plan view of the lapping machine showing the relative relation and disposition of the lapping plate, the work carrying plate, the eccentric driving arms and their accessories for driving the lapping plate over the work carrying plate.

Figure 2 is a vertical cross section of the machine shown in Fig. 1, sectioned along the line 2-2 in the direction indicated by the arrows. This shows the relative dispositions of the lapping plate and work carrying plate relative to the driving mechanism.

Figure 3 is a vertical section of the machine shown in Fig. 1, sectioned along the line 3-3 in the direction indicated by the arrows. This shows the arrangement of the driving eccentrics for the operation of the lapping plate over the work carrying plate.

Figure 4 is a vertical section of the machine shown in Fig. 1, sectioned along the line 4-4 in the direction indicated by the arrows, showing the main driving shaft and driving pulley.

Figure 5 is a vertical section of the machine shown in Fig. 1, sectioned at the line 5-5 in the direction indicated by the arrows. This shows the arrangement of the operating parts which accomplish the shifting of the path of the lapping plate, relative to the work carrying plate, and which arrangement permits any desired change of the position of the path to be made during the operation of the machine in lapping, etc.

In Figure 1, the lapping plate 2 is driven over the work carrying plate 1 in a desired and prescribed manner by the pin 3 which is carried in an adjustable clamping holder 51 secured to the bar 25 which is in turn secured to the hinge fork 24, hinging upon the bearing collar 23 on the driving pin 22. The bar 25 carries the adjustable blocks 47 and 46 with the tightening screws 48, forming the ball socket bearing for the bar 45. This bar is secured by screws 52 to the bar 43 which in its turn is secured to hinge fork 42 hinging upon the bearing collar 41 on the driving pin 40. This pin 3 is driven from the two driving pins 22 and 40, and has a free movement vertically to be lifted out of the lapping plate 2 when desired. The ball and socket joint of bar 45 in block 47 may be adjusted over a limited amount as desired along the bar 25 and clamped in position by screws 48 bearing upon piece 46 thus clamping the edges of the tube 25 between 46 and 47.

Driving pin 40 is adjustably secured in a slot of the arm 53 securely fastened to the vertical spindle 44. Below the arm 53 the arm 39 is securely fastened to the spindle 44. This arm 39 is in turn connected to the rod 37 by pin 38, making a hinge joint. This rod 37 is in turn connected to the driving eccentric or slotted plate 16 by the pin 35. By having pin 35 adjustable in slot 36 of plate 16 the spindle 44 may be given an oscillating movement dependent upon the adjustment of pin 35 in the slot 36. Also driving pin 40 thus is actuated through spindle 44 and arm 53 from the eccentric 16. Driving pin 40 also has adjustment of position in slot in arm 53 thus enabling a further adjustment of the stroke of pin 40 when clamped securely to arm 53. The pin 22 fits into the slot 62 of arm 21 which is firmly secured to and oscillates about the axis spindle 20. The arm 19 is also firmly secured to the spindle 20, thus oscillation of arm 19 imparts oscillation to the arm 21 and the desired movement to the pin 22. Arm 19 is connected by pin 49 to the eccentric rod 18 which also forms the eccentric strap for the main driving eccentric 17. The eccentric 17 and the eccentric plate 16 are each securely attached to the vertical spindle 55, as shown in Fig. 3.

Spindle 55 carries the firmly secured driving gear 15 engaged by the worm or gear pinion 14 rigidly mounted upon the driving shaft 10, which in turn is connected by the

handle 12 of the clutch 11 to the driving pulley 13. Thus the power for the movement of the pin 3 for lapping plate 2 is delivered from the main driving pulley 13, 5 through the clutch 11 to shaft 10 and from the shaft 10 to spindle 55, which carries the two eccentrics 17 and 16, etc.

Referring to Fig. 2 in addition to Figs. 1 and 3, the work carrying plate 1 is securely 10 fastened to the vertical spindle 56, to which is secured the driving gear 4 in mesh with the worm pinion or gear pinion 5 secured on shaft 50 which carries at the outer end the hand wheel 34 and at the other end the clutch 15 6 operated by lever or control 7. Thus the separate section of shaft 50 carrying gear 8 driven by gear 9 secured on main driving shaft 10, may be connected or disconnected at the will of the operator. In this manner 20 work carrying plate 1 may be rotated by the hand wheel 34 at the will of the operator, or left to drive automatically while pin 3 operates the lapping plate 2.

Referring to Figs. 4 and 5, in connection 25 with Fig. 1, the axis spindle 20 has a working bearing in arm 26 which is securely fastened to vertical axis 57. Arm 26 carries also the yoke holding the screw thread bearing 28 by swivel screws 27 for the screw 30 shaft 29. This screw shaft 29 has at its end near work carrying plate 1, a hand wheel 33 and a swivel bearing 31 on swivel centers 32, also a thrust collar 30. Thus with the arm 21 securely fastened to the axis 20 as well 35 as the arm 19, and with axis 20 free to oscillate in its bearing in arm 26; the arm 26 can be slowly oscillated about axis 57 by the hand wheel 33 at the will of the operator at all stages of the machine operation. Thus 40 also by operating hand wheel 33, axis 20 may be oscillated about axis 57 through any desired angle without interfering with the strokes of the pin 22, having only the effect of shifting the position of the orbit of the 45 pin 3 and of lapping plate 2 over the work carrying plate 1. Also by shifting the position of the path of strokes of tool pin 3 and lapping plate 2 by operating the handwheel 34, a completely controlled localization of 50 lapping effort may be brought to any desired part of work carrying plate 1.

While I have described the preferred embodiment of my invention, and have illustrated the same in the accompanying drawings, certain minor changes or alterations 55 may appear to one skilled in the art to which this invention relates, during the extensive manufacture of the same and I, therefore, reserve the right to make such alterations or 60 changes as shall fairly fall within the scope of the appended claims.

The invention having been described, what is claimed is:

1. In a grinding and lapping machine 65 of the character described, the combination

of a work carrying plate, a lapping plate positioned above said work carrying plate, a pin engaging said lapping plate, a driven spindle, a pair of eccentrics keyed upon said spindle, a bar connected to said pin, 70 a bell crank structure having an arm connected with the end of said bar, a pitman rotatably carried by one eccentric and connected with another arm of the bell crank structure whereby longitudinal movement 75 will be imparted to said bar, and means for imparting transverse movement to the bar including a pitman having connection with the other eccentric for rotary movement 80 thereon during rotation of the eccentric. 85

2. In a grinding and lapping machine of the character described, the combination of a work carrying plate, a lapping plate positioned above said work carrying plate, a pin engaging said lapping plate, a bar connected to said pin, a driven spindle, 90 a pair of eccentrics keyed upon said spindle and extending in opposite directions, means adjustably connecting one of said eccentrics to one end of said bar and including a collar portion rotatably fitting about the periphery of the eccentric, and means adjustably connected with the remaining eccentric for movement radially 95 thereof and serving to adjustably connect the last mentioned eccentric to said bar intermediate the ends thereof, whereby the bar will be driven so that the lapping plate will be moved in a variable manner, as and 100 for the purposes set forth.

3. In a grinding and lapping machine of the character described, the combination of a work carrying plate, a lapping plate positioned above said work carrying plate, a pin engaging said lapping plate, a bar connected to said pin, a driven spindle, a pair of eccentrics keyed upon said spindle, one of said eccentrics having a driving slot, 105 a rod having means on one end adjustably mounted in said slot, and means on the remaining end of said rod adjustably connecting said rod to said bar intermediate the ends of the bar, and means having a portion rotatably mounted about the periphery of the other eccentric, said means serving to connect the last mentioned eccentric to the end of the bar, whereby the bar may 110 be driven so as to move the lapping plate in a variable manner, as and for the purposes set forth. 115

4. In a grinding and lapping machine of the character described, the combination of a work carrying plate, a lapping plate positioned above said work carrying plate, a pin engaging said lapping plate, a bar connected to said pin, a driven spindle, a pair of eccentrics keyed upon said spindle, 120 a rod adjustably connected to one of said eccentrics, a vertical axis spindle, an arm pivotally mounted upon said axis spindle 125

and pivotally connected to said rod, a slotted arm mounted upon said first-mentioned arm, a second bar connected to the first-mentioned bar, means adjustably connecting the second-mentioned bar to said slotted arm, and means connecting the remaining eccentric to the end of the first-mentioned bar, as and for the purposes set forth.

5. In a grinding and lapping machine of the character described, the combination of a work carrying plate, a lapping plate positioned above said work carrying plate, a pin engaging said lapping plate, a bar connected to said pin, a driven spindle, a 10 pair of eccentrics keyed upon said spindle, said bar being of a tube-like construction and being slotted, blocks movably mounted within and without said bar, set screws engaging said blocks for holding the same 15 in an adjusted set position, a second bar connected to said blocks, thereby being adjustably connected to the first-mentioned bar, means connected to one of said eccentrics and to said second-mentioned bar for 20 driving the same, and means connecting the remaining eccentric to the end of the first-mentioned bar, whereby the first-mentioned bar will be driven so as to move the 25

lapping plate in a variable manner, as and for the purposes set forth.

6. In a grinding and lapping machine of the character described, the combination of a work carrying plate, a lapping plate positioned above said work carrying plate, a pin engaging said lapping plate, a bar 30 connected to said pin, a driven spindle, a pair of eccentrics keyed upon said spindle, means adjustably connecting one of said eccentrics to said bar intermediate the ends 35 of the bar, a frame-like rod connected to the remaining eccentric, a fixed vertical axis, an arm pivotally mounted upon said axis, a screw shaft adjustably connected to the arm at one end thereof for adjusting said arm, an axis spindle carried by 40 said arm intermediate its ends, a second arm connected to said frame-like rod and to said axis spindle, and means adjustably connecting said axis spindle to the end of 45 said bar, whereby the bar will be driven 50 so as to impart variable strokes to said lapping plate, as and for the purposes set forth.

In testimony whereof I hereunto affix my signature.

FLOYD CALVIN WEAVER.
